MATERIAL-TREATING MACHINE

Application filed June 8, 1927. Serial No. 197,301.

This invention relates to material mixing, disintegrating or homogenizing machines, and particularly to a machine adaptable for use as a commercial drink mixer for preparing soda fountain types of drinks, or as a domestic appliance for similar purposes.

It has been found that when a conglomerate or partial mixture of different liquids or a similar mixture of liquids and comparatively easily dissoluble solids is passed between two comparatively smooth closely adjacent noncontacting surfaces, moved as by rotation, past each other at high velocity, say 10,000 to 15,000 R. P. M., such partial mixture may be quickly converted into a homogeneous liquid mass. The present machine uses this principle of operation and comprises essentially a rotor element and a stator element together with a suitable casing arranged to conduct the material to be mixed, or otherwise treated, to between the rotor and stator surfaces and conducting the mixed or treated material away from such surfaces.

In the use of such a machine for mixing drinks, one of the problems that has arisen is that of cleaning the machine of material, such as fruit pulp, seeds or the like which by reason of their indissolubility and the close proximity of the surfaces, will not pass between the surfaces, but which stay in the receiving chamber of the machine. An object of the invention is to so arrange the machine that it may be readily and accurately operated for cleaning without being taken apart, and easily and accurately readjusted after the cleaning operation.

It has previously been proposed to axially move the rotor element to thus separate the surface sufficiently to allow the pulp, etc. to be flushed out past the surfaces, but this has several disadvantages. For example, the rotor is usually well inside the casing and is therefore hard to get at. In the present invention cleaning is accomplished by moving a part of the casing with reference to another part in such manner that the surfaces are substantially separated, the relation of the casing parts being such that this

movement is immaterial so far as retaining material in the casing is concerned.

Further objects include the provision of a mixing or disintegrating machine of the general character shown, which will be simple to manufacture, easily and quickly adjusted for cleaning purposes and easily adjusted to minutely vary the distance between the rotor and stator surfaces to enable the machine to effectively operate on materials of different character.

In these machines it is old to provide preliminary disintegrating and agitating means in the material receiving chamber portion of the casing to partially disintegrate solid material before the material reaches the rotor and stator surfaces and to partially mix the different ingredients. The usual arrangement consists of lateral projections on a shaft rigid with the rotor. A further object is to provide a device in connection with the material receiving chamber, in which the arrangement of elements will oppose the natural tendency of the whirling material to climb the walls of the chamber, and which will forcibly urge the material toward the rotor and stator surfaces.

Another object consists in the provision of an improved and simplified form of material treating surfaces.

Further objects will hereinafter appear and the various features of the invention will be fully explained in the following description relating to the accompanying drawing showing the preferred forms. The essential characteristics will be summarized in the claims.

In the drawing, Fig. 1 is a sectional side view of the complete machine, the sectionally illustrated parts being broken away along a central vertical plane; Fig. 2 is a side elevation of the machine showing a modification with respect to the means for separating the rotor and stator surfaces for cleaning; Fig. 3 is a transverse sectional view as indicated by the line 3-3 on Fig. 2, and Fig. 4 is a fragmentary view similar to Fig. 1 showing a modified arrangement of rotor and stator surfaces.

Referring in detail to the drawing 1 is the

general frame of the machine, shown as comprising a hollow casting having a base 2 adapted to rest on a table or counter, the portion 3 of the base being extended to support a receptacle, such as indicated at G. 5 The casting has upper and lower hollow portions 4 and 5, the former serving as the discharging chamber for mixed materials and the latter as a housing for an electric motor disposed below the discharge chamber. 10 The armature of such motor is shown at 20, the shaft being extended as at 21. The hollow portions 4 and 5 are divided by a transverse wall 6 having its upper surface 7 inclined downwardly at a rather steep angle toward the side of the discharge spout 8, shown as formed integrally with the hollow portion 4 and projecting downwardly therefrom over the base portion 3. The end of 15 the spout may have transverse webs as at 8^a for acting on the mixed material which naturally travels down the spout in a rapidly whirling condition, imparted to it by the rotor. The webs serve to overcome this 20 condition.

The rotor surface 22 is supported by a rotor member 23 attached to the motor shaft, as will be presently shown, and the stator surface 10 is carried by an annular 25 portion 11 of the casing member 12 which forms the receiving chamber for material to be mixed or disintegrated. The receiving chamber is formed similar to a funnel at the top, and the annular portion 11 has 30 a skirt-like portion 13 arranged to enter the partially cylindrical bore 14 at the top of the main casing portion 4. The stator surface 10 is normally positioned very close to the cooperating surface 22 on the 35 rotor 23, but does not contact therewith. As shown the mixing or disintegrating surfaces are generally planar and will be 40 more fully discussed later.

The preferred means for quickly separating the rotor and stator surfaces for 45 cleaning comprises comparatively steep coarse threads 15 engaging complementary threads formed in the casing portion 4 above the cylindrical bore 14. Thus, by giving the member 12 a partial turn the surfaces 10 and 22 will be considerably separated. When the surfaces are thus separated the machine may be flushed out and 50 thus cleaned, simply by throwing a quantity of cleansing fluid into the member 12 while the motor is operating. The above mentioned preliminary disintegrating means, to be later referred to in detail, assists in the 55 cleaning operation, as will be obvious from inspection of Fig. 1.

For adjustably limiting the downward movement of the member 12, I preferably provide an outwardly extending flange 16 arranged to contact with an adjustable 60 abutment ring 17, threaded as at 18 on ex-

ternal threads near the top edge of the casing portion 4. These threads should be comparatively fine in order that a slight turn of the ring will only slightly alter the distance between the material treating surfaces. A locking ring or jam nut 19 may be provided adjacent and below the ring 18 to hold the ring 18 in place against accidental movement when once it is properly adjusted. Suitable graduations may be provided on the portion 4 of the casing and on the locking ring 19, as shown at 4^a and 19^a in Fig. 4, or other convenient indicating means may be used.

The threads 15 should be determined, as 70 to their inclination with reference to the direction of rotation of the motor because if the rotation of the member 12 in bringing the surfaces toward each other, is the same as the direction of the rotation of the motor; then when once the flange 16 is seated on the ring 17, the frictional drag transmitted through the material fed between the surfaces from the rotor to the stator will 75 simply tend to further seat the flange on 80 the abutment ring. The use of fine threads at 18 and coarse (therefore steeper) threads as at 15, has this advantage, namely, that when turning the member 12 to raise the stator surface the flange does not tend to 85 drag the ring 17 along with it which might otherwise disturb the adjustment.

The rotor 23 previously mentioned, has a hub 24 which may be threaded as at 25 to the armature shaft 21. The hub rests on a 90 shim or washer 26, which in turn rests on a shoulder 21^a formed on the shaft. Extending upwardly from the top of the rotor is a stub shaft 27 threaded as at 28 to the 95 rotor and having a cone point 29 entering a conical and central recess 30 in the top of the motor shaft. The cone and recess provides for keeping the shaft 27 and the shaft 25 in alignment and also acts as a locking member to hold the rotor solidly onto the 100 motor shaft. The stub shaft 27 serves to support the preliminary disintegrating and agitating means which as shown comprises suitable projections, one being indicated at 105 32. The shaft 27 may also have members 110 similar to threads, such as 34 to urge material downwardly toward the rotor. Near the bottom of the stub shaft is a pin 35 passing through the shaft and positioned 115 close to the top surface of the rotor for 120 forcibly throwing material outwardly toward the gap between the rotor and stator surfaces.

To utilize the whirling condition of the material in the receiving chamber (due to 125 the action of the projections 32) to urge the material downwardly, I provide helical ribs 40 on the inside surface of the receiving chamber. The height, degree of inclination and spacing of the ribs is determined 130

with reference to the consistency of material to be treated and the speed of operation of the motor; the relationships shown being suitable for treating ordinary drink mixtures. The walls of the receiving chamber member may be formed to provide a restriction as at 41 above the projections 32, the chamber becoming larger below the restriction and then converging at the bottom. When the receiving chamber is charged with material and the motor started, the material will be rapidly churned by the members 32, wherefore it will cling to the inside surfaces of the chamber. The restriction 41 will assist in overcoming the tendency of the whirling material to climb the walls of the chamber, while the ribs act on the outermost portion of the rapidly revolving mass of material to urge the material downwardly toward the rotor and stator surfaces. The suction generated by the surfaces themselves, due to centrifugal force, is of course a very active element in feeding the material.

25. A convenient means for preventing material in the discharge chamber, namely, within the casing portion 4, from following the shaft, consists in providing an upwardly extending tubular member 50 surrounding the shaft 25. To reduce friction on the shaft the tube is in spaced relation to the shaft as at 51. It will be noted that this spaced apart relation continues along the shaft to a point just above the upper bearing 52 for 30 the shaft. The top of the tube 50 is positioned close to the bottom surfaces of the hub of the rotor, or more properly to the washer 26. When the motor is operating at high speed, it will be easily understood 35 that none of the mixed material can get into the space 51 and thus follow the shaft into the motor because of the action of centrifugal force on any medium disposed between the top surface of the tube 50 and the adjacent surface of the washer. To prevent the suction thus induced from draining oil from the bearing I provide an air inlet opening at 53 above the bearing. The air projected into the discharge chamber assists 40 in dislodging the mixed material from the chamber. This would be unnecessary if the material were always thin, but when the material is thick or sticky it becomes important.

55. Suitable means for controlling the motor may comprise a switch 60 having a controlling element 61 arranged to be depressed toward the motor housing against a spring (not shown) in order to operate the motor. To conveniently operate the switch either 60 by hand or by manipulation of the material receiving receptacle G, I provide a lever 62 having its upper end 63 arranged to contact with the controlling element 61 and having its lower end projecting forwardly as at 65 65 to a position beneath the receptacle. With

this arrangement, as the operator places the receptacle under the discharge spout 8, he may simply press downwardly with it on the end of the lever, carrying it into a suitable recess 67 in the base portion 2, thus starting the motor. When the receptacle is removed, the motor will automatically stop.

The particular form and arrangement of the mixing or disintegrating surfaces, is immaterial so far as the above described mechanism is concerned, since obviously any shape or arrangement of material treating surfaces may be used, such as are well known in this art. However, my improved arrangement of mixing surfaces includes one or more slight grooves on one or both of the material treating surfaces preferably on the rotor. As shown, a single outward spiral 70 is cut or etched into the top of the rotor, 75 the groove beginning as at 71 and extending substantially to the outer edge of the rotor, near 73. The direction of spiral is determined with reference to the direction of rotation so that when the rotor turns the 80 groove appears to travel inwardly. The groove may be formed to provide close convolution at the outer edge of the rotor in order to increase the frictional drag on the material as the centrifugal force increases. 85 The two closely positioned surfaces will act on the material to move it outwardly toward the periphery of the rotor but at the same time the spiral groove prolongs the mixing or disintegrating operation. This arrangement or its equivalent is especially useful 90 on the general type of surfaces shown since with the planular surfaces the centrifugal force is greater than with almost any other shape, assuming of course substantially the same areas and diameters. In the case of 95 two smooth planular mixing surfaces of the comparative size shown, the mixing operation would ordinarily be exceedingly rapid but by reason of the groove or grooves, additional capillary attraction on the material results; and because the groove or grooves travel inwardly, there is in addition considerable actual shearing force acting to and in tearing solid and semi-solid materials apart, so well as to hold back the film of material against the action of centrifugal force.

A modified form of separating means for the rotor and stator surfaces, is shown in Figs. 2 and 3 wherein 80 indicates a bail hinged as at 81 to the housing portion 4, and having connections with the annular portion 11 by reason of pins 82 engaging slots 83 in the bail. Suitable means for holding the bail in downward position, in which position the surfaces may be considered in operating position, may comprise an eye bolt 85 pivoted at 86 and having a thumb nut 87 adapted to engage the top of the bail and clamp it in its lowered position. The shank 120 125 130

of the eye bolt preferably rests in a partially circular recess 88 at the free end of the bail and the bail may be doubled flat as at 89 to provide a handle for raising and lowering it.

5 In Fig. 4, I have shown a different arrangement of agitating means. In this case, the stub shaft 27^a may have any suitable number of cross members 90, each arm of 10 which is inclined upwardly with reference to respective planes of rotation. This arrangement aids the helically formed ribs 45 in urging the material downwardly toward the material treating surfaces. In this form the 15 material is first fed straight downwardly from the bottom of the receiving chamber to the main material treating surfaces through a constant gap 92, this gap determining the size of particles which may be fed between 20 the material treating surfaces, irrespective of the adjustment between the latter surfaces. To guide the material into the gap, the sides 25 of the material receiving chamber may slope inwardly as at 94 and the rotor may join the shaft 27^a in a cone shape as at 95.

I claim:

1. In a machine of the class described, a stationary housing member, a rotor in axially fixed relation to and supported by the housing, said rotor having a circular surface, an axially movable housing member comprising a chamber and supporting a surface complementary to the rotor surface and slightly spaced therefrom, and adjustable means 30 interposed between the housing members for fine adjustment between the said surfaces including an abutment rigid with one housing member and an adjusting member cooperable with the abutment and in threaded engagement with the other housing member.

40 2. In a mixing machine, an axially movable tubular member, a stationary tubular support, a rotor and means for driving it carried by the support, circular surfaces supported by the rotor and tubular member in close non-contacting relation, the tubular member being in coarse threaded engagement with the support to effect the relative axial movement, and means in fine threaded 45 engagement with one of the said tubular elements arranged to act as a stop against such relative movement in one direction to minutely govern the distance between the said surfaces.

55 3. In a machine of the class described, a stationary housing member, a movable housing member adjacent thereto and in telescoping engagement therewith, a circular mixing surface supported by one of said members, 60 a rotor and means supported by the other housing member for driving the rotor, the rotor having a mixing surface in close non-contacting relation to the first mentioned surface, a connection between said housing members including an inclined recess in one

member and a tongue carried by the other and engaging the recess, whereby turning movement of the movable housing member in one direction separates said mixing surfaces, and means mounted on one of said members externally thereof and turnable to different positions to limit the movement of the housing members toward each other for fine adjustment between the mixing surfaces.

70 4. In a machine of the character described, a stator having a material treating surface, a rotor having a complementary material treating surface, a casing supporting the stator and formed to provide a chamber, a shaft extending into the chamber and connected to the rotor for driving it, means rigid with the casing and surrounding the shaft in spaced relation thereto, said means presenting a laterally extending surface, means carried by the shaft and having a laterally extending surface in close non-contacting relation to the said surface of the first named means, a bearing for the shaft carried by the casing and means providing an air inlet to the space between the shaft and first named means, whereby oil or the like will not be drawn from the bearing into the chamber by the relative rotation between the laterally extending surfaces.

75 5. In a drink mixer, a tubular casing 90 formed to provide an open inlet at the top and a discharge outlet at the bottom, mixing means disposed intermediate the upper and lower ends of the casing, including rotor and stator elements with their adjacent surfaces in close non-contacting relation, a shaft for driving the rotor, means extending upwardly from the rotor and driven thereby and laterally extending projections carried by the shaft for agitating and disintegrating material contained in the upper portion of the casing, and inwardly projecting means extending about the walls of the casing above the agitating means for deflecting the agitated material downwardly.

100 6. In a machine of the class described, a casing formed to provide a discharge chamber, means carried by the casing and having a downwardly facing circular material treating surface, a rotor having an upwardly facing surface in close non-contacting relation with the first named surface, a shaft for driving the rotor, tubular means above said surfaces for receiving material to be treated and conducting it to the surfaces, means arranged to rotate in a constant direction for agitating material, said agitating means being disposed in said tubular means, said tubular means having a restricted portion disposed above said agitating means and an enlarged portion below the restricted portion for retaining material in the region of the agitating means.

105 7. In a machine for treating liquids and solids in which the material is fed by grav-

- ity, means supporting a pair of closely adjacent non-contacting surfaces including a rotor, means for turning the rotor at high speed, a tubular charging chamber having its inner surface substantially circular and terminating at its lower edge adjacent one of said surfaces, a shaft extending upwardly from the rotor into the chamber, and abrupt projections carried by the shaft for agitating material in said chamber, the surface of
- 5 the charging member having an arcuate inclined rib extending above the projections whereby material circulated by the agitating means is urged downwardly toward the closely adjacent surfaces.
- 10 8. In a machine of the class described, a tubular casing means, means in the casing for supporting a circular material treating surface, a rotor and means for driving it at high speed, the rotor having a substantially planular surface in close non-contacting relation to the stator surface, said surfaces being substantially equidistantly spaced, and means including a spiral recess in one of the
- 20 material treating elements arranged to frictionally oppose the passage of material between the said surfaces.
- 25 9. In a mixing machine, separate means for supporting two generally planular closely adjacent surfaces and means to rotate one surface past the other at high speed, means to supply material to be treated between said surfaces and for conducting and discharging the treated material, one of said surfaces having a spirally formed recess arranged to frictionally oppose the passage of material between the surfaces to thereby prolong the treating operation.
- 30 10. In a mixing machine of the class described, a tubular casing open at the top to receive material to be mixed, mixing means associated therewith and disposed at the bottom of the casing and including a stator surface rigid with the casing, and a rotor in close association with a stator surface, means
- 35 below the casing including a shaft and connections therefrom to the rotor for rapid rotation thereof, means projecting upwardly from the rotor into the casing, arranged to agitate material in the casing to preliminarily disintegrate material before the same is passed between the rotor and stator surfaces, and inclined means rigidly associated with the casing and spaced from the disintegrating means for causing the material to be deflected downwardly toward the rotor and stator surfaces.
